UNITED STATES PATENT OFFICE.

JAMES B. EDWARDS, OF COLUMBIA, SOUTH CAROLINA, ASSIGNOR OF ONE-HALF TO
ALEXANDER M. GIBBES, OF COLUMBIA, SOUTH CAROLINA.

GRATE-BAR.

1,096,697.

Specification of Letters Patent.

Patented May 12, 1914.

Application filed May 3, 1911. Serial No. 624,740.

To all whom it may concern:

Be it known that I, JAMES B. EDWARDS, a citizen of the United States, residing at Columbia, in the county of Richland and 5 State of South Carolina, have invented new and useful Improvements in Grate-Bars, of which the following is a specification.

An object of the invention is to provide a grate bar for fireplaces and the like so 10 that an air space will be provided beneath the grate bar proper and the same will be retained in proper position.

For the purpose mentioned, use is made of an apertured grate body and a base, the 15 said grate body being adapted to rest on the said base and having portions spaced therefrom to provide an air space.

Reference is to be had to the accompanying drawings constituting a part of this 20 specification, in which similar characters of reference denoting corresponding parts in all the views, and in which—

Figure 1 is a plan view of my device. Fig. 2 is a longitudinal section. Fig. 3 is a 25 view looking at the under side of the grate body. Fig. 4 is a plan view of the base, one of the prongs thereof being bent outwardly at an angle to the base.

Referring more particularly to the views 30 I provide a grate body 10 having the usual apertures 11 therein, and integrally formed on the ends of the grate body 10 are solid flanges 12, an integral supporting flange 13 being formed at the middle portion of the 35 grate body 10 and depending from the under side thereof for a purpose that will be hereinafter more fully disclosed. Integrally formed on the grate body 10 adjacent the ends 12 thereof are retaining flanges 14 ex- 40 tending downwardly and outwardly from the grate body 10 and forming a space 15 be- 45 tween the outer flanges 12 and the retaining flanges 14. A base 16 is provided having the outer ends thereof bent upwardly to form prongs 17 having their ends 18 bent inwardly toward each other as shown in Fig. 2.

In the use of my device, the prongs 17 are first bent slightly outward and the grate

body 10 is then disposed in position on the 50 base 16 so that the supporting flange 13 will repose approximately on the middle portion of the base 16 and on the upper side thereof, thus spacing the remaining parts of the 55 grate body 10 from the base 16. The prongs 17 are then bent inwardly so that the ends 18 will be received in the spaces 15 formed by the flanges 12 and the flanges 14. The 60 grate body 10 and the base 16 will now be relatively connected as will be seen by refer- 65 ring to the views, air spaces 19 are formed between the grate body 10 and the base 16 and between the prongs 17 of the base 16. By providing the air spaces 19 as mentioned, when the grate bar described is used, the 65 grate body 10 will be at all times prevented from becoming very warm owing to currents 70 of air circulating through the air spaces 19 and flowing upwardly through the apertures 11, thus also increasing the combustible efficiency of any fuel disposed on the upper side of the grate body 10.

Should the grate body 10 for any reason 75 wear out, a new grate body can be easily positioned to replace the old grate body by bending the prongs 17 outwardly and removing the old grate body and then positioning the new grate body in place of the old one and rebending the prongs to engage the retaining flanges 14 as heretofore de- 80 scribed, thus securing the new grate body in the proper manner relatively to the base 16. Should the grate body for any reason be- 85 come overheated it will be prevented from bending by the supporting flange 13, which, resting on the base 16 will substantially support the grate body in rigid position.

Having thus fully described the invention, what I claim as new, is:—

In a grate bar, the combination with a 90 grate body, of a base, a supporting flange depending from the under side of the grate body at the medial portion thereof and en- 95 gaging the base to support the grate body thereon, retaining flanges formed on the ends of the grate body and projecting out- 95 wardly from the under side thereof, flanges formed on the ends of the grate body and

projecting outwardly beyond the retaining flanges to provide spaces between the retaining flanges and the last mentioned flanges, and prongs projecting upwardly from the 5 ends of the said base and bent around the said retaining flanges to extend into the said spaces.

In testimony whereof I affix my signature in presence of two witnesses.

JAMES B. EDWARDS.
